UNITED STATES PATENT OFFICE.

CHARLES LUTHER BOUTON, OF CHICAGO, ILLINOIS, ASSIGNOR OF ONE-HALF
TO WILLIAM S. KENNY, OF SAME PLACE.

MAGAZINE PLATE-HOLDER.

SPECIFICATION forming part of Letters Patent No. 660,180, dated October 23, 1900.

Application filed January 9, 1899. Serial No. 701,571. (No model.)

To all whom it may concern:

Be it known that I, CHARLES LUTHER BOUTON, of Chicago, in the county of Cook and State of Illinois, have invented certain new and useful Improvements in Magazine Plate-Holders; and I do hereby declare that the following is a full, clear, and exact description thereof, reference being had to the accompanying drawings, and to the letters of reference marked thereon, which form a part of this specification.

This invention relates to improvements in magazines or plate-holders for photographic cameras.

The invention consists in the matters hereinafter described, and set forth in the appended claims.

Figure 1 shows in perspective a view of a magazine embodying my invention. Fig. 2 is a broken section taken on line 2 2 of Fig. 1 with the cover of the magazine closed. Fig. 3 is a section taken on line 3 3 of Fig. 1 with the cover of the magazine closed. Fig. 4 is an elevation of the lower part of the side of the magazine-case. Fig. 5 is a section taken on line 5 5 of Fig. 4. Fig. 6 is a vertical section of the magazine, showing the position of the same when opened for the first exposure. Fig. 7 is a section similar to that shown in 30 Fig. 6.

A indicates a hinged light-proof magazine-case or inclosure within which are located a series of plate-carriers B B, which are permanently connected at their lower edges with each other and with the front and rear walls of the inclosure by a flexible connecting-strip B', which forms a flexible or hinged connection between said parts, as the leaves and covers of a book are joined by its binding.

To said plate-carriers may be either permanently or removably attached the sensitive plates b b, with which the magazine is loaded. The magazine-case has the form of an inclosure, of pasteboard or other suitable material, adapted to cover the plate-carriers and plates at their front and rear faces and side and top margins, so as to exclude light therefrom, and consists of a rear wall C', provided with forwardly-extending flanges C² C³ 45 C⁴ on its side and top margins, and a front wall C⁵, provided with similar rearwardly-

extending marginal flanges C⁶, C⁷, and C⁸. The flanges of the rear and front walls meet each other when the case is closed and preferably overlap, the flanges of the front wall fitting over those of the rear wall as the flanges of a box-cover fit over a box-body. As shown, the said flanges are of the same width, and the said front wall, with its lateral flanges, is adapted to so clearly fit about the flanges of the rear wall as to exclude light when the case is closed. The said magazine-case or inclosure is without any bottom except that formed by the flexible connecting-strip B', which is made of leather, cloth, or other flexible material and being attached to the lower margins of the plate-carriers and front and rear walls serves, when the case is closed, to exclude light at the bottom of the case. In order to form a close joint between the ends of the strip B' and the side flanges of the front and rear walls of the inclosure, strips of felt b' are secured to the end of said strip in such manner as to project beyond the same, and the lower margins of the side flanges C⁶ and C⁸ of the front wall are provided with similar projecting felt strips c c. When the case is closed, the strips b' on the hinged strip B' come in contact with the lower edges of the flanges C² C⁴ of the rear wall and also with the similar strips c c on the flanges of the front wall, thereby making close joints at these points to insure the exclusion of light from the plates. It is obvious that by this construction a case or inclosure is provided having overlapping walls on three sides and a flexible bottom attached to the rear and front wall, but in no wise attached to the said flanges, so that the case may be opened by throwing the front wall away from the plate-carriers to expose the latter, and the plate-carriers may be successively thrown forward away from those behind them to expose the several plates in the same manner that a book is opened and its leaves turned. The walls of the case or inclosure will preferably be lined with black paper to exclude light.

The plate-carriers B B may be made in any suitable way to receive and hold the plates. As herein shown, they are made of paper or the like and are joined to the flexible or hinged strip B' directly or by means of strips

of paper or cloth, one edge of each being firmly cemented to the bottom edge of one of the said plate-carriers and the other edge thereof being cemented to the inner surface of the hinged strip in such manner as to provide an individual hinge for each plate-carrier, uniting the same to the flexible strip b' . The plate-carriers and their inclosure or magazine-case constitute an article which is separate from but adapted to fit into a camera and which may be filled with sensitive plates and so long as it remains closed may be kept for any length of time and carried to any distance without liability of the plates being affected by light and may be inserted into a camera while still closed and opened after the camera is closed by suitable devices within the camera, thereby affording a means of loading or filling a camera in daylight or sun-light and making it unnecessary to perform the operation of loading in a dark room.

To enable the plate-carriers to operate properly in connection with devices provided in a camera for moving or feeding and successively exposing the plates in the focal plane, said carriers are made as follows: The said plate-carriers may be and are herein shown as made of the same width as the plates to be secured thereto. The carriers are, however, higher than the plates and, as herein shown, are rectangular and approximately of the same length and width as the interior of the rear part of said inclosure and extend above the upper margins of the plates. The latter are shown as made of glass and cemented upon the front side of the said plate-carriers, which when the plates are of glass need not themselves have any special rigidity, but may be of thin cardboard or the like, except in their portions which extend above the plates, which are made of relatively stiff or thick material. As herein shown, strips b' of pasteboard or other suitable material having the same thickness as the plates are secured to the carriers above the upper edges of said plates. The upper margins of the said plate-carriers are provided with notches b' , arranged alternately on opposite sides of a central line in such manner that a suitable stop or detent by being moved laterally to left and right may be made to operate alternately upon each of the said plate-carriers, successively releasing the forward plate-carrier and holding the next succeeding one in the focal plane of the camera with which it is used until it is exposed.

As a further improvement a spring b' , Fig. 3, is interposed between the rear wall of the magazine-case or inclosure and the plate-carriers therein in such manner that it tends to throw the upper edges of the plate-carriers or plates outwardly or forwardly from the said rear wall. The said spring conveniently consists of a light spirally-coiled wire secured to the inner face of said rear wall.

A magazine-case constructed as described

is adapted to be inserted in any suitably-constructed camera and by means of suitable mechanism may be opened after the camera is closed, the plates successively exposed, and the magazine-case closed before the camera is opened for the removal of the same.

My invention when used in a camera is designed to rest upon a support which will elevate the bottom thereof to a height above the bottom of the camera equal to the width of the gauge C .

Owing to the staggered arrangement of the notches of the upper margin of the plate-carriers on each side of a central line a suitable 80 detent within the camera in which the magazine is used may successively hold and release the plates by a lateral movement thereof toward the right and left, respectively, and after each of said movements of the detent 85 the plate-carrier last exposed falls downward upon the preceding one, and the remaining plates may be slid forward by the action of a spring or other suitable means, and the plates as they successively fall forward into 90 the front closure of the magazine-case assume successively the position shown in Figs. 6 and 7. Owing to the flexible connection of the plate-carriers and front and rear walls of the said magazine-case, as the plates fall successively forward the magazine-case slides bodily forward on the support, and any return 95 or backward movement of the said case or the plates therein, in case the camera should be held in position to produce such movement, may be prevented by the holding action of a spring or other suitable means attached to the camera. When the last plate in the magazine has been exposed, the detent or other means which has held the plate-carriers 100 successively during the exposure may be disengaged from the carriers, thereby releasing the rear wall of the magazine-case and permitting the same to be thrown or fall forwardly, thereby closing the magazine-case 105 and preventing access of light to the plates when the camera is opened.

I claim as my invention—

1. The combination of a plurality of flexibly-connected plate-carriers and an inclosure 115 for the said plate-carriers made larger than and adapted to surround the carriers adapted to exclude light therefrom during transportation and handling and to be opened to expose the plates after the plates with the inclosure 120 have been inserted in a camera.

2. The combination of a plurality of plate-carriers and a two-part inclosure for the same made larger than and adapted to surround the carriers; said plate-carriers and the parts 125 of the inclosure being flexibly connected at their bottom edges.

3. A plate-holder comprising a plurality of plate-carriers, front and rear walls having flanges at their side and top edges which extend over the side edges of the carriers and overlap to form an inclosure for the plates 130.

and a flexible section secured to and connecting the lower edges of the plate-carriers and the said front and rear walls.

4. A plate-holder comprising a plurality of plate-carriers, front and rear wall flanges at their side and top edges to form an inclosure for the plate-carriers and a flexible section joining the lower edges of the plate-carriers and of said front and rear walls, the flanges of one of said walls and the ends of the flexible section being provided with flaps of flexible material adapted when the front and rear walls are closed, to meet for the purpose of excluding light from the plates.
5. The combination of a plurality of plate-carriers, plates permanently secured thereto, flanged front and rear walls adapted to surround and to form an inclosure for the plate-carriers and plates, and a flexible section adapting the lower edges of the said plate-carriers with the lower edges of said front and rear walls.
6. The combination of a plurality of plates,

plate-carriers to which said plates are attached, said plate-carriers being extended beyond the plates at their upper margins, and front and rear walls flanged to form an inclosure for the plates said plate-carriers and the front and rear walls being flexibly joined to each other at their lower edges.

7. The combination of a plurality of plate-carriers, flanged front and rear walls forming an inclosure adapted to completely surround the plate-carriers, said plate-carriers and front and rear walls being flexibly joined to each other, and a spring interposed between the said rear wall and said plate-carriers.

In testimony that I claim the foregoing as my invention I affix my signature, in presence of two witnesses, this 5th day of January, 1899.

CHARLES LUTHER BOUTON.

Correction in Letters Patent No. 660,180

It is hereby certified that in Letters Patent No. 660,180, granted October 23, 1900, upon the application of Charles Luther Bouton, of Chicago, Illinois, for an improvement in "Magazine Plate-Holders," an error appears in the printed specification requiring correction, as follows: In the heading the words and figures "Serial No. 701,571," should read *Serial No. 701,577*; and that the said Letters Patent should be read with this correction therein that the same may conform to the record of the case in the Patent Office.

Signed, countersigned, and sealed this 30th day of October, A. D., 1900.
